PLASTIC SHEET MATERIAL OR THE LIKE

Wallis E. Stuart, Hingham, Mass., assignor to Air Reduction Company, Incorporated, New York, N.Y., a corporation of New York

Filed Nov. 7, 1962, Ser. No. 72,418

Term of patent 14 years

(Cl. D87—3)

The single figure is a plan view of a plastic sheet material incorporating my new design, the repeat unit of which is substantially contained between the two horizontal dash lines and the two vertical dash lines.

I claim:

The ornamental design for a plastic sheet material or the like, as shown and described.
